DESIGN FOR A COMBINED INKWELL AND PENHOLDER

Ernest Oldenbusch, Jr., Rockville Centre, N. Y.

Application May 23, 1936, Serial No. 62,798

Term of patent 7 years

To all whom it may concern:

Be it known that I, Ernest Oldenbusch, Jr., a citizen of the United States, residing at Rockville Centre, in the county of Nassau and State of New York, have invented a new, original, and ornamental Design for a Combined Inkwell and Pen Holder, of which the following is a specification, reference being had to the accompanying drawing, forming part thereof.

Figure 1 is a perspective view of a combined

inkwell and pen holder, showing my new design.

Figure 2 is a front elevational view thereof,

Figure 3 is an end elevational view thereof, and

Figure 4 is a top plan view of the same.

I claim:

The ornamental design for a combined inkwell and pen holder, as shown.

ERNEST OLDENBUSCH, JR.
